INTERVAL TIMER

William P. Gallagher and Paul G. Bielik, Chicago,
Ill., assignors to International Register Company,
Chicago, Ill., a corporation of Illinois

Application March 29, 1950, Serial No. 152,545

20 Claims. (Cl. 161—23)

1

This invention relates generally to timing mechanisms, more particularly to the kind used for actuating an alarm and/or a switch after a predetermined interval of time.

There are many occasions where it is desirous to have a signal or a switch or some other device actuated after the lapse of a predetermined interval of time. For many of these occasions the interval may be very small—perhaps a matter of a few minutes, possibly even less than a minute. On other occasions the time interval may be several hours.

For example, in the modern home kitchen the housewife may wish to have set off a sound or visual signal after the lapse of two or four minutes needed for the boiling of eggs. At other times she may desire such a signal to operate after the lapse of a quarter or half hour. At still other times she may wish to have such a signal after the lapse of two, three, or four hours, or possibly after an hour and a certain number of minutes.

In other situations it may be desired to operate a switch controlling a coffee percolator, a radio, or a fan.

Timing mechanisms of this kind heretofore provided to operate after a lapse of more than an hour have not been useable for accurately operating a signal or switch for a small span of time, such as two or three minutes. Such timing mechanisms heretofore provided for operating signals or switches after a lapse of a small interval of time have not been suitable for use for operating such devices after a lapse of more than an hour. Accordingly, where situations demanded the operations of mechanisms for both small and long intervals of time two devices have had to be used, or one has had to be content with inexactness in the operation of one.

The main objects of this invention, therefore, are to provide:

An improved form of timing mechanism which permits the setting thereof for actuation after the lapse of either a very small or a rather extended period of time;

A mechanism of this kind in which the setting means may be operated in either a clockwise or a counter-clockwise direction with almost equally accurate results;

A device of this kind which may be assembled with a conventional clock mechanism operating the usual hour and minute hands or which may be used entirely independent of the conventional clock mechanism; and

An improved form of device of this kind wherein the several parts are few in number, exceed-

2

ingly simple to manufacture and assemble and the operation of which is very obvious and the results are highly certain.

In the accompanying drawings—

5 Fig. 1 is a front elevation of an interval timer constructed in accordance with this invention as used in connection with a conventional clock mechanism and dial;

Fig. 2 is a side elevation of the same;

10 Fig. 3 is a front elevation of the mechanism embodying this invention, the view being taken on the plane of the line 3—3 of Fig. 2;

15 Fig. 4 is a partly sectional, partly elevational view of the mechanism shown in Fig. 3 as viewed from the plane of the line 4—4 of Fig. 3;

Fig. 5 is an enlarged, cross-sectional detail of the time wheel and its clutch-connected operating gear constructed in accordance with this invention;

20 Fig. 6 is an exploded view of the timing mechanism constructed in accordance with this invention as associated with a conventional clock mechanism and dial such as shown in Fig. 1;

Fig. 7 is an enlarged detail of the time wheel 25 setting and signal releasing means;

Fig. 8 is a front elevation of an interval timer constructed in accordance with this invention when used independently of the conventional clock mechanism and dial;

30 Fig. 9 is an elevational view of the mechanism used for the device shown in Fig. 8 and taken on the same plane as the view shown in Fig. 3; and

Fig. 10 is an enlarged cross-sectional detail of the timing wheel and its clutch-connected operating gear constructed in accordance with this invention for use without the conventional clock mechanism; and

35 Fig. 11 is an exploded view of the construction shown in Figs. 8—12.

40 A timing mechanism constructed in accordance with this invention comprises a mounting A, in the form of a housing, whereon are arranged dials B and C, a motor D, and in which is enclosed the setting and release mechanism E, and with which 45 mechanism gearing F may or may not be used to operate the conventional minute and hour hands of a clock.

The mounting A is a sheet metal stamping formed with a chamber 11 rearwardly offset from 50 a substantially rectangular shaped peripheral flange 12 and to which is secured a cover plate 13 whereon are mounted the dials B and C and between which is arranged the usual cover glass 14.

The base 15 of the offset part of the mounting 55 A, which forms the chamber 11, is apertured at

certain points in alignment with apertures in the cover plate 13 to provide bearings for certain of the operating parts of this improved timing mechanism; also, this base mounts pins 16 and 17 which serve as bearings for certain other parts of the mechanism. Lugs 18, 19, 20 and 21 struck up from the base 15 provide support for certain parts of the setting and release mechanism E, as will appear presently.

The housing flange 12 is likewise apertured at certain points to receive screws, whereby the plate 13 is secured in place, and to receive lugs on the dial C for securing it in place.

The motor D as herein shown is a synchronous electric motor, enclosed in a suitable housing. It is removably attached to the base 15 so as to position a driven pinion 22 in the chamber 11 for meshing with the timing wheel 23 of the setting and release mechanism E and the hour and minute hand gearing F when that is associated with this improved setting and release mechanism.

The dial B, as herein shown, is a disk preferably enameled, secured to the cover plate 13 generally by an adhesive. For either of the embodiments herein shown the dial is scored or otherwise marked to indicate sixty minutes. In the embodiment shown in Figs. 1 and 6, the dial B also bears numerals representative of five-minute divisions beginning and ending with "60" at the normal twelve-hour position and extending counter-clockwise. For the modification shown in Figs. 8 and 11, numerals representative of the five-minute divisions are omitted. At the normal six-hour position, this dial for either embodiment bears the word "hours" and the numerals 0 to 4 arcuately arranged with respect to a knob 26 constituting a part of the setting and release mechanism E.

The dial C is in the form of a ring and is secured to the cover plate 13 by lugs 25 extending through suitable apertures in the cover plate 13 and the mounting flange 12 which lugs are bent over against the back of the flange 12. For the embodiment shown in Figs. 1 and 6 the dial C bears the conventional numerals representative of the hours. For the modification shown in Figs. 8 and 9 the dial bears, in counter-clockwise direction, the numerals indicative of ten-minute divisions. The numeral 30 is omitted because of the knob 26.

The provision of the alternative outer dial C, indicating the division of an hour into minutes, makes it possible to use this interval timer on equipment with which there is already associated a conventional time piece. This avoids the confusion that would ensue, with two time pieces on one piece of equipment, if this interval timer were useable only when associated with a conventional time piece.

The time setting and release mechanism E comprises the timing wheel 23, in the form of a gear, a time wheel setting and signal control shaft 27, a tripper 28, and an hour-adjusting means 29.

The timing gear 23 mounts on the reverse side thereof a smaller gear 30 (Fig. 5) adjustably held in place by a diaphragm disk 31 which serves as a clutch to permit the rotation of the gear 23 independently of the gear 30. The gear 30 is formed and positioned to mesh with the motor driven pinion 22 so that the timing wheel 23 makes a complete revolution in one hour. On the face of the gear 23, opposite the gear 30, is mounted a pawl 60 pivoted at 61 and normally

urged by a spring 62 to swing a transverse shoulder 63 into the path of an hour-adjusting means 29. A stop shoulder 64 on a lug 65 punched forwardly from the body of the gear 23 is adapted to be engaged by the shoulder 63 of pawl 60 to limit the outward swing of the pawl on its pivot 61.

When this improved interval timer is to be used with gearing for operating a conventional time piece (as will be explained presently) the hub of the time gear 23 is made hollow so as to receive the minute and hour shafts (see Fig. 5). However, when the timer is used with the alternative dial C of Fig. 8, the hub of the timing gear 23 is made solid, and longer on the underside to compensate for the space occupied by the gearing F to be described presently.

The time setting and signal control shaft 27 is axially shiftable and rotatably mounted on the housing base 15 and the cover plate 13. A pinion 32 is positioned so as to mesh with the timing wheel 23 and rotate the same when the shaft 27 is in its elevated or extended position. At its inner end the shaft 27 is recessed at 33 to form a pair of cam surfaces 34 and 35 adjacent the respective hub parts 36 and 37 and which coact to control the operation of the signal S.

The shaft 27 is shouldered at 38, 39, and 40. The shoulder 38 coacts with the tripper 28 whereby the shaft 27 is held in its elevated or extended position with the pinion 32 in mesh with the timing gear 23. The shoulder 39 is engaged by the end of a spring 41, which bears against the housing base 15, and normally urges the shaft 27 toward its inward or retracted position. The intermediate shoulder 40 is tapered (see Fig. 7) and coacts with the periphery of the hole in the housing base 15, through which the shaft 27 extends to arrest the shaft, when released by the tripper 28 after being elevated to set the timing wheel 23, and hold said shaft short of its fully retracted position. The hole in the base 15 through which the shaft 27 extends is slightly larger than the shaft so that it can be urged by a leg 42 of a spring 43 held on the housing lug 21 to cause such contact of the shoulder 40 with the housing base 15.

A knob 44 is suitably secured to the end of the shaft 27 to permit the axial and rotatable adjustment thereof.

The tripper 28, as most clearly shown in Figs. 6 and 11, is somewhat in the nature of a bell crank lever having arms 45, 46, and 47, extending angularly of each other from a connecting base part. The arms 46 and 47 are spaced apart and are apertured to permit the tripper to be swingably supported on the housing pin 17. The tripper 28 is normally urged in a counter-clockwise direction by the spring 43 to position the shoulder 48 on the arm 45 to engage the shoulder 38 on the shaft 27, when it is elevated and thus hold it in that retracted position. Incidentally, the leg 42 of the spring 43 is normally urged against the periphery of the shaft 27 to engage the shoulder 40 as hereinbefore explained. The leg 49 of the spring 43 is caught under a lug 50 on the tripper arm 47.

The arm 46 is arcuate-shaped and extends over toward the hour adjusting means 29, being provided at its end with a lug 83 to be actuated thereby, as will more fully be pointed out hereinafter.

The hour adjusting means 29 comprises a pair of sector-shaped ratchets 51 and 52 mounted on

a shaft 53 journaled on the housing base 15 and the cover plate 13. The end of the shaft 53 extends out through the dial C and mounts a knob 54 with a pointer 55. The knob 54 permits the shaft 53 to be oscillated to position the ratchets 51 and 52 to effect the desired postponement of the release of the shaft 27. The pointer 55 alines itself radially with the "hour" numerals on the dial B to indicate the period of the postponed release of the shaft 27 after its elevation.

The ratchet 51 is formed with four teeth 56 which, when the ratchet 51 is rotated clockwise, are positioned in the path of the shoulder 63 on the pawl 60. The subsequent engagement of the pawl shoulder 63 with the teeth 56 results in a counter-clockwise movement of the ratchet 51 which eventually effects a shifting of the tripper to release the shaft 27. It will be noted that there are as many teeth 56 on the ratchet 51 as there are "hour" markings at the bottom of the dial B.

The ratchet 52 is formed with depressions 57 to correspond with the teeth 56. The depressions coat with a V-shaped offset 58 in the spring 59 supported on the lugs 18, 19 and 20 to hold the ratchet 51 in any of its three adjusted positions away from its zero ("0") or normally retracted position. This ratchet member 52 is provided at one end with a laterally projecting lug 82 adapted to impart tripping motion to the adjacent lug 83 on the tripper 28, as will be later described.

The gearing F is of conventional form for operating the minute and hour hands of a clock. It comprises a gear 66 with a pinion 67, a gear 68 with a pinion 69, and gear 70. The gear 66 is journaled on the housing base 15 at the center of the chamber 11 and meshes with the motor driven pinion 22. It mounts a shaft 71 to which is fixed a minute hand 72. The gear 68 is an idler journaled on the pin 16 and meshes with the pinion 67. The gear 70 is journaled on the shaft 71 and meshes with the pinion 69. The gear 70 mounts a shaft 73 on which is fixed an hour hand 74.

A shaft 75 is journaled on the housing A with a pinion 76 meshing with the gear 68. The shaft 75 mounts a knob 77 whereby the gearing F may be manually actuated to set the hands 72 and 74 to indicate the proper time.

A pointer 78 is adapted to be secured to the hub of the timing gear 23 to traverse the dial B for indicating the interval of time for which the setting and release mechanism E is adjusted.

The signal S, as herein shown, comprises an armature 79 mounted on a spring arm 80 secured to the base of the housing for the motor D. A tongue 81 on the arm 80 is positioned to be engaged by the hub parts 36 and 37 or be free in the recess 33. The armature 79 extends into the field winding of the motor D whereby—when the field is energized—the armature tends to reciprocate so as to cause a vibration of the arm 80, thus constituting an audible signal if the tongue 81 is in the recess intermediate the hub parts 36 and 37. When the shaft 27 is in either of its extreme positions the tongue 81 is engaged by one or the other of the hub parts 36 or 37 so that the armature 79 is immobilized and the signal S will remain silent.

Where desired, the end of the shaft 27 could be arranged to effect in some other manner the sounding of a signal or the operating of a switch to control a circuit.

The operation of the improved interval timer herein shown is substantially as follows:

When it is desired to set the device to operate the signal S, after a given interval of time, the knob 44 is pulled out from the face of the dial C. This elevates or extends the shaft 27 axially against the action of the spring 41 and brings the pinion 32 into mesh with the timing gear 23. Thereupon the knob 44 may be rotated in either direction to move the pointer 78 away from the "starting point" "60" to correspond with the interval of time it is desired to have lapse before the signal is to be sounded. The elevation of the shaft 27 shifts the hub part 37 into contact with the tongue 81 on the arm 80 and thereby immobilizes the signal S.

The knob 44 is marked with an arrow indicating that the rotation of the shaft 27 should be clockwise. Although this is the preferred direction of rotation, the shaft can be rotated in the opposite direction with substantially the same efficient results as can be obtained by turning the shaft 27 in a clockwise direction. The only difference in the time interval of the release of the shaft 27, between turning one way or the other is the lag in the meshing of the gear 30 with the pinion 22. One of the advantages in being able to turn the knob 44 in a counter-clockwise direction is that the pointer 78 may be set with less turning of the knob 44 if the time interval before the actuation of the signal is greater than one-half hour.

If the desired interval of time is less than an hour, only the knob 44 is actuated to elevate the shaft 27 and adjust the pointer 78 to the point on the dial B, representative of the time to elapse before the signal S is to sound.

If the interval of time which it is desired to have elapse after the setting and before the sounding of the signal is more than an hour, the knob 54 is also turned clockwise so as to shift the hour setting means 29 for one, two, or three hours. This moves the teeth 56 into the path of the shoulder 63 on the time wheel pawl 60.

It should be understood that there is no imperative sequence of the actuation of the knobs 44 and 54. It also should be understood that the ratchet 51 is normally in position to locate the first tooth (from the right) 56.1 in position to be engaged and be retracted by the travel of the pawl shoulder 63 past the point diametrically opposite the registration of the pointer 78 with "60" on the dial B. Moreover, it should be understood that the time may be set for an even number of hours (and no minutes) or a given number of hours (not more than three for the instant instruction) and a given number of minutes up to and including 60.

This adjustment of the pointer 78 by the knob 44 rotates the time gear 23 so that the shoulder 63 on the pawl 60 is circumferentially removed from the aforesaid point of its retracting engagement with the ratchet tooth 56.1 a distance corresponding with the interval of time that is to elapse before the signal is to be freed. When, during the rotation of the time gear 23 by the motor D (always clockwise), the pawl shoulder 63 approaches a point diametrically opposite the starting point numeral "60" on the dial B, it will contact the ratchet tooth 56.1 and so shift the ratchet 51 that at the instant the cam shoulder 63 is diametrically opposite said starting point the ratchet 51 will have been shifted sufficiently to cause the shoulder 82 on the ratchet 52 to engage the shoulder 83 on the arm 46 of the tripper.

per 28 and swing the tripper 28 against the action of the spring leg 49 so as to retract the shoulder 48 on the arm 45 out of the path of the shoulder 38 on the shaft 27. This will permit the spring 41 to shift the shaft 27 toward its retracted position. Its full retraction, however, will be arrested by the engagement of the tapered shoulder 40, on the shaft 27, with the mounting base 15 (see Fig. 7) into which position the shaft 27 is urged by the spring leg 42. The shaft 27 being thus arrested locates the recess 33 so that the tongue 84 of the arm 80 is free of the shaft hubs 36 and 31, whereupon the field of the motor D will reciprocate the armature 19 thus vibrating the arm 80 sufficient to make an audible signal.

The signal S is silenced by a depression of the shaft 27 so that the leg 42 of the spring 43 is cammed out of contact with the shoulder 49 which permits the spring 41 to fully retract the shaft 27. When thus fully retracted the tongue 84 of the arm 80 is engaged by the hub 36 and the signal is thereby immobilized.

When this timer is set for more than an hour the contact of the pawl shoulder 63 with the tooth 56.1 is delayed until said pawl shoulder has contacted one or more of the other teeth 56 and shifted the ratchets 51 and 52 one or more points depending upon how far the ratchets 51 and 52 were shifted clockwise.

Other variations and modifications in the details of structure and arrangement of the parts may be resorted to within the spirit and coverage of the appended claims.

We claim:

1. A timing mechanism comprising, a mounting, a motor driven element, a time wheel, means connecting said time wheel to said driven element to cause a complete revolution from a starting point in a predetermined period of time, said means including a clutch permitting said wheel to be rotated independently of said driven element, means for setting said wheel in any desired position away from said starting point to permit a subsequent rotation of said wheel by said driven element through a predetermined portion of a complete revolution, or through more than one revolution, ratchet means adapted to be preset for selectively obtaining a timing interval of less than an hour or more than an hour, pawl means carried by said time wheel and arranged to actuate said ratchet means once for a timing interval of less than an hour and arranged to actuate said ratchet means more than once for a timing interval of more than an hour, and a device activated by said ratchet means.

2. A timing mechanism comprising, a mounting, a motor driven element, a time wheel, means connecting said time wheel to said driven element to cause a complete revolution from a starting point in a predetermined period of time, said means including a clutch permitting said wheel to be rotated independently of said driven element, means movable into position for setting said wheel in any desired position away from said starting point to permit a subsequent rotation of said wheel by said driven element through a predetermined portion of a complete revolution, means for automatically retracting said setting means when said wheel is returned to said starting point, manually adjustable means interposed between said wheel setting means and said retracting means for delaying the action of said retracting means until after one or more full revolutions of said wheel, and a device activated by said setting means.

3. A timing mechanism comprising, a mounting, a motor driven element, a time wheel, means connecting said wheel to said driven element to cause a complete revolution from a starting point in a predetermined period of time, said means including a clutch permitting said wheel to be rotated independently of said driven element, a normally-retracted wheel-setting member shiftable into position to engage said wheel to permit turning of said time wheel away from said starting point to secure a subsequent rotation of said wheel by said element through a predetermined portion of a complete revolution, means for releasably holding said member in engagement with said wheel, a pawl on said wheel positioned to engage and release said member-holding means when said wheel is returned to said starting point, and a device actuated by the release of said member.

4. A timing mechanism comprising, a mounting, a motor driven element, a time wheel, means connecting said wheel to said driven element to cause a complete revolution from a starting point in a predetermined period of time, said means including a clutch permitting said wheel to be rotated independently of said driven element, a normally-retracted wheel-setting member shiftable into position to engage said wheel to permit turning of said time wheel away from said starting point to secure a subsequent rotation of said wheel by said element through a predetermined portion of a complete revolution, means for releasably holding said member in engagement with said wheel, a pawl on said wheel positioned to engage and release said member-holding means when said wheel is returned to said starting point, and a device actuated by the release of said member.

5. A timing mechanism comprising, a mounting, a motor driven pinion, a time gear connected with said driven element so as to complete a revolution from a starting point in a predetermined period of time, said connection including a clutch permitting said gear to be rotated independently of said driven pinion, an axially shiftable shaft rotatably journaled on said mounting, a pinion on said shaft for meshing with said time gear to permit turning of said time gear away from said starting point to secure a subsequent rotation of said time gear by said driven element through a predetermined portion of a complete revolution, means normally urging said shaft axially to disengage said pinion from said time gear, a knob for axially shifting and rotating said shaft, a shoulder on said shaft, a tripper normally urged into position to engage said shoulder for holding said pinion in mesh with said time gear, a pawl on said time gear, a shouldered member oscillatingly journaled on said mounting adjacent said time gear so as to locate one shoulder in the path of said pawl and a second shoulder in position to contact said tripper whereby the engagement of said one shoulder by said pawl causes said second shoulder to retract said tripper from said shaft shoulder, and a device actuated by the release of said shaft.

6. A timing mechanism comprising, a mounting, a motor driven pinion, a time gear connected with said pinion to make one complete rotation from a starting point in an hour, said connection including a clutch permitting said time gear to

be rotated independently of said pinion, an axially shiftable shaft journaled on said mounting, a pinion on said shaft adapted to engage said time gear to permit the turning of said time gear away from said starting point to secure a subsequent rotation of said time gear by said driven pinion through a predetermined portion of a complete revolution, means normally urging said shaft axially to disengage said shaft pinion from said time gear, a shoulder on said shaft, a tripper normally urged in position to engage said shoulder for holding said shaft pinion in mesh with said time gear, a pawl on said time gear, a pair of axially-spaced sector-shaped ratchets oscillatingly journaled on said mounting and positioned so that the teeth on one of said sectors are in the path of said pawl, means on said mounting yieldingly engaging said other ratchet to position the teeth of said first ratchet in the path of said pawl, a shoulder on said other ratchet positioned to engage said tripper when said time gear pawl contacts the last of said teeth on said first-mentioned ratchet whereby said tripper is actuated to release said axially shiftable shaft to disengage said shaft pinion from said time gear, and a device actuated by the release of said shaft.

7. A timing mechanism comprising, a mounting, a motor driven pinion, a time gear connected with said pinion to make one complete rotation from a starting point in an hour, said connection including a clutch permitting said time gear to be rotated independently of said pinion, an axially shiftable shaft journaled on said mounting, a pinion on said shaft adapted to engage said time gear to permit the turning of said time gear away from said starting point to secure a subsequent rotation of said time gear by said driven pinion through a predetermined portion of a complete revolution, means normally urging said shaft axially to disengage said shaft pinion from said time gear, a pawl on said time gear, a tripper in the form of a bell crank lever hinged on said mounting, shoulders on said axially shiftable shaft and said tripper adapted to co-act to hold said shaft in its extended position to locate said shaft pinion in mesh with said time gear, a spring normally urging said tripper to position the shoulder thereon in the path of said shaft shoulder, a member oscillatingly journaled on said mounting adjacent said time gear and having spaced shoulder parts located on opposite sides of said time gear, the shoulder on one of said parts being located in the path of said time gear pawl to be engaged thereby when said time gear reaches its starting point, the shoulder on said other part being positioned to contact said tripper for actuating the same to release said axially shiftable shaft, and a device actuated by the release of said shaft.

8. A timing mechanism comprising, a mounting, a motor driven element, a time wheel, means connecting said wheel to said driven element to cause a complete revolution from a starting point in a predetermined period of time, said means including a clutch permitting said wheel to be rotated independently of said driven element, a normally-retracted wheel-setting member shiftable into position to engage said wheel to permit turning of said time wheel away from said starting point to secure a subsequent rotation of said wheel by said element through a predetermined portion of a complete revolution, means for releasably holding said member in engagement with said wheel, a pawl on said wheel positioned to engage and release said member-holding means

when said wheel is returned to said starting point, a signal, a signal control member, and a cam on said wheel-setting member adapted to contact said control member and immobilize said signal when said wheel-setting member is in engagement with said wheel but release said signal control member to permit the operation of said signal when said wheel-setting member is released.

9. A timing mechanism comprising, a mounting, a motor driven pinion, a time gear connected with said driven pinion so as to complete a revolution from a starting point in a predetermined period of time, said connection including a clutch permitting said time gear to be rotated independently of said driven pinion, an axially shiftable shaft rotatably journaled on said mounting, a pinion on said shaft for meshing with said time gear to permit turning of said time gear away from said starting point to secure a subsequent rotation of said time gear by said driven pinion through a predetermined portion of a complete revolution, means normally urging said shaft axially to disengage said shaft pinion from said time gear, a knob for axially shifting and rotating said shaft, a shoulder on said shaft, a tripper normally urged into position to engage said shoulder for holding said shaft pinion in mesh with said time gear, a pawl on said time gear, a shouldered member oscillatingly journaled on said mounting adjacent said time gear so as to locate one shoulder in the path of said pawl and a second shoulder in position to contact said tripper whereby the engagement of said one shoulder by said pawl causes said second shoulder to retract said tripper from said shaft shoulder, a pair of axially spaced hubs on said shaft, a signal, and a signal control member positioned on said mounting to be engaged by said hubs when said shaft is in either limit of its axial movement and immobilize said signal but be disengaged by said hubs to permit the operation of said signal when said shaft is in a position intermediate the limits of its axial movement.

10. A timing mechanism comprising, a mounting, a motor driven pinion, a time gear connected with said driven pinion so as to complete a revolution from a starting point in a predetermined period of time, said connection including a clutch permitting said time gear to be rotated independently of said driven pinion, an axially shiftable shaft rotatably journaled on said mounting, a pinion on said shaft for meshing with said time gear to permit turning of said time gear away from said starting point to secure a subsequent rotation of said gear by said driven pinion through a predetermined portion of a complete revolution, means normally urging said shaft axially to disengage said shaft pinion from said time gear, a knob for axially shifting and rotating said shaft, a shoulder on said shaft, a tripper normally urged into position to engage said shoulder for holding said shaft pinion in mesh with said gear, a pawl on said time gear, a shouldered member oscillatingly journaled on said mounting adjacent said time gear so as to locate one shoulder in the path of said pawl and a second shoulder in position to contact said tripper whereby the engagement of said one shoulder by said pawl causes said second shoulder to retract said tripper from said shaft shoulder, the inner end of said shaft being recessed to provide a pair of opposed axially spaced hubs, a signal, and a signal control member positioned on said mounting to be engaged by either of said hubs to immobilize said signal control member when said shaft is in either

limit of its axial movement but be disengaged by both of said hubs to permit the operation of said signal when said shaft is intermediate the limits of its axial movement.

11. A timing mechanism comprising, a mounting, a motor driven pinion, a time gear connected with said driven pinion so as to complete a revolution from a starting point in a predetermined period of time, said connection including a clutch permitting said time gear to be rotated independently of said driven pinion, an axially shiftable shaft rotatably journaled on said mounting, a pinion on said shaft for meshing with said time gear to permit turning of said time gear away from said starting point to secure a subsequent rotation of said time gear by said driven pinion through a predetermined portion of a complete revolution, means normally urging said shaft axially to disengage said shaft pinion from said time gear, a knob for axially shifting and rotating said shaft, a shoulder on said shaft, a tripper normally urged into position to engage said shoulder for holding said shaft pinion in mesh with said time gear, a pawl on said time gear, a shouldered member oscillatingly journaled on said mounting adjacent said time gear so as to locate one shoulder in the path of said pawl and a second shoulder in position to contact said tripper whereby the engagement of said one shoulder by said pawl causes said second shoulder to retract said tripper from said shaft shoulder, a pair of axially spaced hubs on said shaft, a signal, a signal control member positioned on said mounting to be engaged by said hubs when said shaft is in either limit of its axial movement and immobilize said signal but be disengaged by said hubs to permit the operation of said signal when said shaft is in a position intermediate the limits of its axial movement, another shoulder on said shaft, and yieldable means normally pressing radially on said shaft to cause said other shoulder to contact said mounting and arrest the axial movement of said shaft when released by said tripper whereby to position said hubs to permit the operation of said signal, said yieldable means being retractable from said other shoulder by pressure applied to said shaft whereby said signal is immobilized by the shifting of said shaft to the inner limit of its axial movement.

12. A timing mechanism comprising, a mounting, a motor driven pinion, a time gear connected with said driven element so as to complete a revolution from a starting point in a predetermined period of time, said connection including a clutch permitting said time gear to be rotated independently of said driven pinion, an axially shiftable shaft rotatably journaled on said mounting, a pinion on said shaft for meshing with said time gear to permit turning of said time gear away from said starting point to cause a subsequent rotation of said time gear by said driven pinion through a predetermined portion of a complete revolution, means normally urging said shaft axially to disengage said shaft pinion from said time gear, a knob for axially shifting and rotating said shaft, a shoulder on said shaft, a tripper normally urged into position to engage said shoulder for holding said pinion in mesh with said time gear, a pawl on said time gear, a shouldered member oscillatingly journaled on said mounting adjacent said time gear so as to locate one shoulder in the path of said pawl and a second shoulder in position to contact said tripper whereby the engagement of said one shoulder by said pawl causes said second shoulder to retract said tripper from said shaft shoulder, a signal, a signal control member positioned on said mounting to be inactivated by said shaft when in either limit of its axial movement, a cam shoulder on said shaft, and yieldable means normally pressing radially on said shaft to cause said cam shoulder to contact said mounting and arrest the axial movement of said shaft when released by said tripper and hold it short of its fully retracted position to permit the operation of said signal, said yieldable means being retractable to release said cam shoulder from engagement with said mounting by pressure applied to said shaft axially.

13. A timing mechanism comprising, a mounting, a motor driven pinion, a time gear connected with said driven element so as to complete a revolution from a starting point in a predetermined period of time, said connection including a clutch permitting said gear to be rotated independently of said driven pinion, an axially shiftable shaft rotatably journaled on said mounting, a pinion on said shaft for meshing with said gear to permit turning of said time gear away from said starting point to cause a subsequent rotation of said time gear by said driven pinion through a predetermined portion of a complete revolution, means normally urging said shaft axially to disengage said shaft pinion from said time gear, a knob for axially shifting and rotating said shaft, a shoulder on said shaft, a tripper normally urged into position to engage said shoulder for holding said pinion in mesh with said gear, a pawl on said time gear, a shouldered member oscillatingly journaled on said mounting adjacent said time gear so as to locate one shoulder in the path of said pawl and a second shoulder in position to contact said tripper whereby the engagement of said one shoulder by said pawl causes said second shoulder to retract said tripper from said shaft shoulder, a signal, a signal control member positioned on said mounting to be inactivated by said shaft when in either limit of its axial movement, a cam shoulder on said shaft, and yieldable means normally pressing radially on said shaft to cause said cam shoulder to contact said mounting and arrest the axial movement of said shaft when released by said tripper and hold it short of its fully retracted position to permit the operation of said signal, said yieldable means being retractable from engagement with said mounting by pressure applied to said shaft axially.

14. A timing mechanism comprising, a housing, a motor driven pinion, gearing mountable on said housing for actuation by said pinion to move hour and minute hands, two pairs of concentrically arrangeable dials mountable on said housing, one dial of each pair being scored for minutes whereas the other dial of one pair bears numerals representing the hours 1-12 arranged clockwise and the other dial of the other pair bears numerals representing periods of minutes in counterclockwise order, two pairs of clutch-connected gears of differing diameters mountable in said housing for meshing one gear of each pair with said driven pinion to effect the rotation of said pairs of gears from a starting point in one hour, a normally retracted axially-shiftable and rotatable shaft, a pinion on said shaft positioned for engagement with the larger of either pair of said clutch-connected gears to permit turning of the larger gear away from said starting point to secure a subsequent rotation of said larger gear by said driven pinion through a predetermined portion of a complete revolution, means for releas-

ably holding said shaft with said shaft pinion in its gear engaging position, a pawl on the larger of each of said pairs of clutch-connected gears, a shouldered member oscillatingly journaled on said mounting so as to locate one shoulder in the path of one of said pawls and a second shoulder in position to contact said means whereby the engagement of said one shoulder by a pawl causes said second shoulder to release said shaft, a device actuated by the release of said shaft, said pairs of said clutch-connected gears being interchangeably positionable in said housing for driving by said driven pinion, a pointer attachable to either of the larger of said pairs of clutch-connected gears whereby said pointer coacts with said second pair of dials for indicating time intervals, and supplemental gearing formed to rotate minute and hour shafts adapted to be interposed between said driven pinion and the other of said pair of clutch-connected gears, and pointers operated by said supplemental gearing to contact with said first-mentioned pointer and said first-mentioned pair of dials for indicating time intervals.

15. A timing mechanism comprising a housing, a motor driven pinion, gearing mountable on said housing for actuation by said pinion to move hour and minute hands, two pairs of concentrically arrangeable dials mountable on said housing, one dial of each pair being scored for minutes whereas the other dial of one pair bears numerals representing the hours 1—12 arranged clockwise and the other dial of the other pair bears numerals representing periods of minutes in counter-clockwise order, two pairs of clutch-connected gears of different diameters mountable in said housing for meshing one gear of each pair with said driven pinion to effect the rotation of said pairs of gears from a starting point in one hour, a normally retracted axially-shiftable and rotatable shaft, a pinion on said shaft positioned for engagement with the larger of either pair of said friction-connected gears to permit turning of the larger gear away from said starting point to secure a subsequent rotation of said larger gear by said driven pinion through a predetermined portion of a complete revolution, means for releasably holding said shaft with said pinion in its gear engaging position, a pawl on the larger of each of said pairs of clutch-connected gears, a shouldered member oscillatingly journaled on said mounting so as to locate one shoulder in the path of one of said pawls and a second shoulder in position to contact said means whereby the engagement of said one shoulder by a pawl causes said second shoulder to release said shaft, a device actuated by the release of said shaft, said pairs of said clutch-connected gears being interchangeably positionable in said housing for driving engagement with said driven pinion, a pointer attachable to either of the larger of said pairs of clutch-connected gears whereby said pointer driven by one coacts with said second pair of dials for indicating time intervals, and supplemental gearing formed to rotate minute and hour shafts adapted to be interposed between said driven pinion and the other of said pair of clutch-connected gears, pointers operated by said supplemental gearing to coact with said first-mentioned pointer and said first-mentioned pair of dials for indicating time intervals, and manually adjustable means interposable between either pair of said clutch-connected gears and said shaft-holding means for delaying the action of said shaft retraction means until after one or

more full revolutions of the respective pairs of connected gears.

16. A timing mechanism comprising, a mounting, a motor driven pinion, a time gear connected with said driven pinion so as to complete a revolution from a starting point in a predetermined period of time, said connection including a clutch permitting said time gear to be rotated independently of said driven pinion, an axially shiftable shaft rotatably journaled on said mounting, a pinion on said shaft for meshing with said time gear to permit turning of said time gear away from said starting point to cause a subsequent rotation of said time gear by said driven pinion through a predetermined portion of a complete revolution, means normally urging said shaft axially to disengage said shaft pinion from said time gear, a knob for axially shifting and rotating said shaft, a shoulder on said shaft, a tripper normally urged into position to engage said shoulder for holding said shaft pinion in mesh with said time gear, a pawl on said time gear, a shouldered member oscillatingly journaled on said mounting adjacent said time gear so as to locate one shoulder in the path of said pawl and a second shoulder in position to contact said tripper whereby the engagement of said one shoulder by said pawl causes said second shoulder to retract said tripper from said shaft shoulder, an annular dial on said mounting arranged with markings in counter-clockwise relation representative of fractions of an hour, and a pointer connected with said time gear to coact with said dial to indicate the portion of a revolution for which said time gear is set to revolve by the actuation of said shaft.

17. A timing mechanism comprising, a mounting, a motor driven pinion, a time gear connected with said driven pinion so as to complete a revolution from a starting point in a predetermined period of time, said connection including a clutch permitting said gear to be rotated independently of said driven pinion, an axially shiftable shaft rotatably journaled on said mounting, a pinion on said shaft for meshing with said time gear to permit turning of said time gear away from said starting point to cause a subsequent rotation of said time gear by said driven pinion through a predetermined portion of a complete revolution, means normally urging said shaft axially to disengage said shaft pinion from said time gear, a knob for axially shifting and rotating said shaft, a shoulder on said shaft, a tripper normally urged into position to engage said shoulder for holding said shaft pinion in mesh with said gear, a pawl on said time gear, a shouldered member oscillatingly journaled on said mounting adjacent said time gear so as to locate one shoulder in the path of said pawl and a second shoulder in position to contact said tripper whereby the engagement of said one shoulder by said pawl causes said second shoulder to retract said tripper from said shaft shoulder, interconnected gearing having shafts concentrically arranged with said time gear and connected to be so driven by said driven pinion that one of said shafts completes a revolution in one hour and the other completes a revolution in twelve hours, pointers fixed to rotate with said pairs of concentric shafts and said time gear, and a pair of dials concentrically arranged on said mounting to be traversed by said pointers, the inner of said dials being scored in counter-clockwise direction to represent fractions of an hour and the outer dial having the conventional hour figures of a clock.

18. In a timer, the combination of a device adapted to be actuated upon the expiration of a selected time interval, which time interval is adapted to be set up on said timer, holding means for holding said device until expiration of said selected time interval, tripping means for tripping said holding means upon the expiration of said time interval, said tripping means having a final tripping position and a plurality of selectable stepping positions in advance thereof from which said tripping means is adapted to be progressively stepped in a restoring direction back into said tripping position, a stepping pawl adapted to impart successive stepping motions to said tripping means, time driven means for imparting motion to said stepping pawl, minute setting means operative to establish a preselected angular relation between said stepping pawl and said time driven means, and hour setting means operative to advance said tripping means to a selected stepping position from which said tripping means is adapted to be stepped by said pawl in a restoring direction back into said tripping position.

19. In timing apparatus, the combination of a device adapted to be actuated upon the expiration of a selected time interval, ratchet means for controlling the actuation of said device, said ratchet means having a tripping position, pawl means for actuating said ratchet means into said tripping position, time driven means, minute setting means for establishing a desired timed relation between said pawl and said time driven means, and hour setting means for positioning said ratchet means whereby one or more ratchet teeth must be engaged by said pawl before said ratchet means reaches said tripping position.

20. In an interval timer adapted to be set selectively either for time intervals of less than an hour or for time intervals of more than an hour,

the combination of time controlled driving means, a time wheel adapted to be driven by said time controlled driving means at a rate to make substantially one revolution in an hour, a tripping pawl carried by said time wheel normally standing at a predetermined starting point in the path of rotation of said time wheel, setting means for setting said time wheel in a backward direction a predetermined distance from said starting point so that for timing intervals of less than an hour it will require the desired time interval for the tripping pawl to be time-driven in a forward direction back to said starting point, ratchet means adapted to be engaged by said tripping pawl when the latter gets back to said starting point, said ratchet means comprising a plurality of teeth including a last tripping tooth, means for presetting said ratchet means whereby said tripping pawl will engage said last tripping tooth on its first return to said starting point for timing intervals of less than one hour, or will engage one or more preceding teeth before engaging said last tripping tooth for timing intervals of more than one hour, and apparatus adapted to be actuated when said tripping pawl engages said last tripping tooth.
